(57) **CLAIM**

The ornamental design for a surgical microscope with stand, as shown and described.

DESCRIPTION

The patent or application file contains at least one drawing executed in color. Copies of this patent or patent application publication with color drawings will be provided by the Office upon request and payment of the necessary fee.

FIG. 1 is a first perspective view of the surgical microscope with stand of our new design;

FIG. 2 is a second perspective view of the surgical microscope with stand of FIG. 1;

FIG. 3 is a rear elevation view of the surgical microscope with stand of FIG. 1;

FIG. 4 is a front elevation view of the surgical microscope with stand of FIG. 1;

FIG. 5 is a top plan view of the surgical microscope with stand of FIG. 1;

FIG. 6 is a right side elevation view of the surgical microscope with stand of FIG. 1; and,

FIG. 7 is a left side elevation view of the surgical microscope with stand of FIG. 1.

The broken lines form no part of the claimed design.

1 Claim, 7 Drawing Sheets
(7 of 7 Drawing Sheet(s) Filed in Color)
